United States Patent Office.

GEORGE R. MOORE, OF LYONS, IOWA.

Letters Patent No. 71,632, dated December 3, 1867.

IMPROVEMENT IN CONSTRUCTION OF CORRUGATED SHEET-METAL BOILERS.

The Schedule referred to in these Letters Patent and making part of the same.

TO ALL WHOM IT MAY CONCERN:

Be it known that I, GEORGE R. MOORE, of Lyons, in the county of Clinton, in the State of Iowa, have invented a new and useful Improvement in Corrugated Boilers; and I do hereby declare that the following is a full and exact description thereof, reference being had to the accompanying drawings, and to the letters of reference marked thereon.

Figure 1 is a longitudinal section of a corrugated copper boiler with my improvement applied.

Figure 2 is an end view of the same.

My invention consists in the application of longitudinal braces, bars, or rods, to stiffen and strengthen boilers endwise, made of copper or sheet metal, and corrugated diametrically.

A is the surface of the boiler, the heads being omitted as not essential to show my invention; B B B B, the longitudinal braces. The ends of the boiler are designed to be inserted in the usual manner, simply creasing them to receive these braces, or adapting them to any other which may be used, so that they are firmly united with the braces.

Having thus fully described my invention, what I claim therein as new, and desire to secure by Letters Patent, is—

The longitudinal braces B B B B, or their mechanical equivalent, in the form of longitudinal bolts or bars, substantially in the manner and for the purposes herein set forth.

Witnesses:

LEWIS GODLOVE,
ROBERT R. MILLS.

GEO. R. MOORE.
